ELECTRIC IRON CONTROL

John R. Gomersall, Elgin, and Murray Ireland, near Elgin, Ill., assignors to McGraw-Edison Company, a corporation of Delaware

Original application April 2, 1945, Serial No. 586,099, now Patent No. 2,585,928, dated February 19, 1952. Divided and this application February 18, 1952, Serial No. 272,223

10 Claims. (Cl. 74—504)

Our invention relates to sadirons and particularly to electrically heated sadirons. The same constitutes one of the various inventions originally included in our prior copending application Serial No. 586,099, filed April 2, 1945, now Patent 2,585,928, to which the present application is related as a divisional application.

An object of the invention is to provide improved manually adjusting control for a heat control switch of an electric iron and of the general type adapted to be operated by a hand holding the iron handle.

Another object of the invention is to provide an improved manual switch adjusting control constructed for convenient assembly with an electric iron.

Another object of the invention is to provide an improved manual switch adjusting control adapted for housing in a hollow column on top of an electric iron body and adapted for easy assembly with such a column.

Another object of the invention is to provide an improved manual switch adjusting control for an electric iron including novel indicating and rotation limiting stop mechanism.

Other objects of our invention will either be apparent from a description of one form of device embodying our invention or will be set forth in the course of such description and particularly in the appended claims.

In the drawings,

Figure 1 is a longitudinal, sectional view through the center of an iron embodying our invention,

Fig. 2 is a top plan view of the indicator in the handle,

Fig. 3 is a lateral, sectional view taken on the line 3—3 of Fig. 1,

Fig. 4 is an enlarged, vertical, sectional view of the handle showing the control parts,

Fig. 5 is a fragmentary, vertical, sectional view taken on the line 16—16 of Fig. 4,

Fig. 6 is a sectional line taken on the line 17—17 of Fig. 4,

Fig. 7 is a top plan view of the parts shown in Fig. 8.

Figs. 8, 9 and 10 are detailed views of the control parts in an exploded arrangement, and,

Fig. 11 is a vertical, sectional view, on a reduced scale, of a modified form of control.

The novel manually adjustable control of the present invention is shown in conjunction with an electric iron construction in accordance with our afore-mentioned application Serial No. 586,099. Such iron comprises a relatively thin metal sole plate 33, a relatively thin top plate 35 and a planar electric heating element 37 sandwiched between such plates. According to our afore-mentioned application, plates 33 and 35 are brazed together under brazing heat and high pressure at their margins to provide a thermally efficient unit. A portion 79 of brazing film which units the margins is shown in Fig. 1 adjacent heel 91 of the sole plate.

Secured in recesses in sole plate 33 and extending upwardly through the top plate are metal assembly or supporting plugs 71 and 73 located in longitudinally spaced

2

relation at the center line of the plates. Mounted on the front plug is a U-shaped supporting bracket 143. Another differently shaped supporting bracket 125 is mounted on rear plug 73. A cover or casing 147 is provided, the lower edge of which is adapted to rest upon the outer peripheral surface of top plate 35. The rear portion of casing 147 is secured to bracket 125 by a single screw 165. A rear closure plate 167 is provided and is held by a single short screw 169 which engages the lower end of bracket 125. The further portion of the iron proper shown in Figs. 1 and 3 includes an automatically operated control switch mechanism for heating element 37. The same includes a lower contact bar 107 and an upper contact bar 121 mounted in insulated relation on rear plug 73. Contact bar 107 extends substantially longitudinally of the iron and has a contact member 127 adjacent its outer end. A coacting contact member 135 is carried by the outer end of contact bar 121. The two bars 107 and 121 are made of spring metal and biased downwardly. An upwardly biased further spring arm 115 is mounted in insulated relation on plug 73 and extends forwardly between contact bars 107 and 121, being apertured for passage therethrough of contact member 135.

The control switch is automatically operated in response to the temperature of sole plate 33 by a diagrammatically shown bimetal thermostat member 43 of sheet material and rectangular shape housed in a chamber or recess 41 in the sole plate and explained in detail in our copending application Serial No. 272,221, filed February 18, 1952, now Patent 2,726,313, dated December 6, 1955, and our aforementioned Patent 2,585,928. A thin metal cover 47 overlies bimetal member 43 and closes the top of chamber 41. An actuating pin 133 engages the midpoint of bimetal member 43 at its lower end and engages at its upper end an insulated bushing 129 on lower contact bar 107. Pin 133 is supported by an insulating bushing 75 secured in top plate 35 and extends downwardly into chamber 41 through a hole in cover 47. The opposite ends of bimetal member 43 are loosely held in position by depressed portions 51 on plate 47. Temperature changes of the sole plate cause the bimetal member to warp vertically and through actuating pin 133 to adjust the position of contact bar 107.

The handle construction includes a main handle grip portion 151 having an integral handle supporting post 153 adjacent its rear end portion and made of a heat and electric insulating material. The rear handle post or support 153 is adapted to be secured to intermediate spacing plate 155 by a plurality of short screws 157 and spacers 159. Plate 155 is adapted to be secured against a cooperating surface of 147 by a plurality of short screws 161, there being spacing members 163 located therebetween. The rear end portion of the handle is adapted to be held in proper position on the casing by the same single screw 165 which, as earlier stated, secures the casing to rear bracket 125.

The structure located below the front end of handle grip portion 151 is independent thereof, the handle being entirely supported through rear supporting post 153. Such structure includes a hollow front member or column 171 of the same material as the handle but formed separately therefrom. The upper end of column 171 is entirely out of engagement with the front end of handle grip portion 151 being slightly spaced therefrom, as shown in Fig. 1. Through such arrangement there is less transmission of heat from the iron body to the front end of the handle grip portion than where the handle is provided, as commonly, with an integral front supporting post.

The lower surface of column 171 has secured there-

against a spacing plate 173 by a plurality of short screws 175 with spacers 177 therebetween. Spacing plate 173 is secured against casing 147 by a single short screw 179 which is threaded in the upper end of bracket 143.

A pair of electric terminals 223 and 225 are secured in a recess 227 in the rear handle post 153, such recess being of substantially L-shape. Plate 119 connects one of such terminals with contact bar 121 of the control switch and a terminal lead 229 connects the other terminal to the electric heating element 37. A single lead connects switch contact bar 107 through a further lead 109 with the heating element. A twin conductor supply cord 231 extends through handle post 153 into recess 227 to connect with terminals 223 and 225. A spring post 233 surrounds cord 231 externally of the handle to prevent kinking. A pair of thumb rests 237 and 239 are provided at the front end of handle portion 151, thumb rest 237 being adapted for a right-handed user, while a left-handed user will use thumb rest 239.

The hollow front column 171 has an opening 181 extending substantially longitudinally therethrough, which opening is adapted to receive means manually-adjustable for changing the position of the spring bar 115 of the control switch for the electric heating element 37 of the iron. Opening 181 has positioned therein a control shaft 183, the lower end portion of which is provided with screw threads for engaging with support 143 so that upon rotary movement of control shaft 183, the lower end portion normally engaging the outer end portion of upwardly biased spring bar 115, will be moved either upwardly or downwardly. The upper end portion of control shaft 183 (Fig. 4) is provided with a short serrated or fluted end portion 185 as well as with an intermediate relatively short portion 187 of reduced diameter. The upper end portion 185 is adapted to fit into an opening 189 in a control wheel hub 191. The control wheel hub has an upper enlarged end portion 193 (Fig. 9) which has a screw driver slot 195 therein for a purpose which will hereinafter appear. The opening 189 is also fluted longitudinally to permit of slidably interfitting engagement with the fluted head 185.

We provide further a control wheel 197 having an inner screw threaded opening therein, which control wheel is adapted to have screwed thereinto the control wheel hub 191. We provide further a control wheel stop member 199 which is provided at its lower end with an opening 201, the inner surface of which is fluted to receive the externally fluted portion 193 of the control wheel hub. The control wheel stop member 199 is adapted to fit over the upper end portion 193 of the control wheel hub and to be held in selectively adjusted position peripherally thereof by a machine screw 203.

The upper end portion of the hollow front column 171 is provided with a recess 205 therein for receiving the control wheel stop 199. A projection 207 is provided intermediate the ends of the control wheel stop 199 and a cooperating projection 209 is provided in recess 205 in a predetermined position to prevent excess peripheral adjusting movements by the operator turning the control wheel.

When assembling the iron, the control shaft 183 may be screwed into the support 143 after which the front column 171 is placed in proper operative on the casting. After this, the control wheel 197 is pushed into the recess provided for it in the column 171 and then the control wheel hub 191 is screwed into the control wheel. The operator then adjusts the position of the control wheel by turning the same until contact 135 just engages contact 127 when the iron is cold. Then he places the control wheel stop 199 with the projection 207 positioned relatively to the projection 209 substantially as shown in Fig. 6 of the drawings, after which he screws in screw 203 tightly.

It is to be noted that the outer periphery of the con-

trol wheel 197 may be provided with flutes 211 for convenience of the operator and that these flutes extend outwardly beyond the periphery of member 171 for engagement by the operator's thumb and finger of the hand holding the iron (Figs. 2 and 6).

A dial 213 is positioned in a recess at the front end of the handle 151. This recess is further provided with covering extensions 215 and 217 extending toward each other and a transparent cover 219 is positioned in the recess thus constituted. A pin 221 is fixedly supported at the front end of handle 151 and is adapted to have interfitting engagement with the dial plate 213 as well as with the cover 219 which is of flexible transparent material.

Referring now to Fig. 11, we have there shown a modification of the manually-actuable switch-adjusting means which we may use instead of that shown in Fig. 4. This adjusting means comprises a control shaft 241 in an opening 243 in member 171, the lower end of which shaft 241 extends through the casing and member 143 and engages the spring arm 115. The upper end of shaft 241 is rigidly connected with a cup-shaped member 245 the upper surface of the wall extending at an angle and having a projection 247 adapted to move in a longitudinal slot 249 and prevent turning movement of member 245. A control wheel hub 251 has its lower end interfitting with an opening in the lower end portion of member 245. A cam member 253 having a lower angularly-extending surface thereon engaged by the angularly-extending surface of the upper end of member 245 is screwed on member 251 against a control wheel 197, which latter abuts an externally fluted head 255 on member 251. A control wheel stop 199 has an opening extending into it from its lower surface, the inner surface of the opening being fluted to engage head 255 in selected position determined by a pointer or arrow mark on member 199, and being held in such position by a screw 203. A spring 257 biases members 245 and 241 so that the two cam surfaces will always be in engagement with each other.

Various modifications may be made in our invention without departing from the spirit or scope thereof and all such modifications coming clearly within the scope of the appended claims are to be considered as part of our invention.

We claim:

1. In an electric iron, a manually adjustable control for the iron electric heat control switch comprising an upstanding control shaft mounted for axial movement, a rotatable hub member separate from the shaft, a rotatable finger adjustable member removably secured to said hub member, a further rotatable member removably secured to said hub member and located above said adjustable member, a rotatable stop element on said further rotatable member, and a stationary stop element coactive with said rotatable stop element.

2. In an electric iron, a manually adjustable control for the iron electric heat control switch comprising an upstanding control shaft mounted for rotary and axial movement, a hub member removably splined to the upper end of said control shaft, a rotatable finger adjustable member removably secured to said hub member and adapted to effect rotary and axial movement of said control shaft, a rotatable stop member removably secured to said hub member and located above said adjustable member, and a stationary stop element coactive with said rotatable stop member.

3. In an electric iron, a manually adjustable control for the electric heat control switch comprising, an upstanding control shaft mounted for axial movement, a housing above the body of the iron having an elongate cavity containing said control shaft, a rotatable finger adjustable member in an opening in said housing lateral of said elongate cavity, a hub member removably fastened to said finger adjustable member for rotation there-

with and lying at least partly in said elongate cavity for holding said finger adjustable member assembled to said housing, and means effecting axial motion of said control shaft in response to rotation of said finger adjustable member and said hub member.

4. The structure of claim 3 wherein there is included a rotatable stop member removably and adjustably secured to said hub member above said finger adjustable member, and a stationary stop element carried by said housing coactive with said stop member for limiting rotation of said finger adjustable member.

5. In an electric iron, a manually adjustable control for the electric heat control switch comprising, an upstanding control shaft threaded for rotation and axial movement in a stationary support carried by the iron, a housing above the body of the iron having an elongate cavity containing at least the upper end of said control shaft, a rotatable finger adjustable member above said shaft in an opening in said housing lateral of said elongate cavity and extending thereto, a hub member in said elongate cavity removably fastened to said finger adjustable member for rotation therewith and for holding it in place and splined to said shaft for rotating it.

6. The structure of claim 5 wherein there is included a rotatable stop member removably and adjustably secured to said hub member above said finger adjustable member, and a stationary stop element carried by said housing coactive with said stop member for limiting rotation of said finger adjustable member.

7. The structure of claim 6 wherein there is included a separate indicator member mounted on said stop member.

8. In an electric iron, a manually adjustable control for the iron electric heat control switch comprising an upstanding elongated control member mounted for axial movement, a separate rotatable hub member adapted through rotation to effect axial movement of said control member, a rotatable finger adjustable member adapted to effect rotation of said hub member, an indicator member removably secured to said hub member and located above said adjustable member, and hollow housing means above the body of the iron enclosing said hub member, said adjustable member and said indicator member, and

from which said indicating member and adjustable member are separately removable.

9. In an electric iron, a manually adjustable control for the iron electric heat control switch comprising an upstanding elongated control member mounted for axial movement, a rotatable finger adjustable member, means responsive to rotation of said adjustable member for effecting axial movement of said control member, an indicating member removably mounted for rotation with said adjustable member and hollow housing means above the body of the iron housing said adjustable member and said indicating member and from which said indicating member and said adjustable member are separately removable.

10. In an electric iron, a manually adjustable control for the iron electric heat control switch comprising an upstanding elongated control member mounted for axial movement, a rotatable finger adjustable member, means responsive to rotation of said adjustable member for effecting axial movement of said control member, a further rotatable member removably mounted for rotation with said adjustable member, and hollow housing means above the body of the iron housing said control member, said adjustable member and said further member and from which housing means said further member is removable separately from said adjustable member and said control member is removable separately from both said further member and said adjustable member.
